HYDROCARBON OIL CONVERSION

Jean Delattre Seguy, Chicago, Ill., assignor to
 Universal Oil Products Company, Chicago, Ill.,
 a corporation of Delaware

Application July 5, 1932, Serial No. 620,776
 Renewed March 10, 1937

10 Claims. (Cl. 196—49)

This invention relates to the treatment of hydrocarbon oils and more particularly refers to an improved process and apparatus for the conversion of raw oil charging stock, flash distillation of the residual products of the system and selective further conversion of the intermediate conversion products of the system, all of which are accomplished simultaneously in a continuous operation.

10 The primary features of the present invention comprise the use of successive cracking stages in a continuous conversion process, raw oil charging stock for the system being supplied to the first conversion stage, which utilizes the mildest conversion conditions employed in the process, while intermediate conversion products (reflux condensate) from each conversion stage is returned to further cracking under more severe conversion conditions than in the succeeding 15 stage of the system, reflux condensate from the last stage being returned to the first stage, together with the raw oil charging stock.

A reaction or separating zone is employed ahead of the fractionating step of each conversion stage of the process and residual oils separated in each of these reaction or separating zones are commingled and subjected to further vaporization or flash distillation at reduced pressure. Vaporous products from the residuum 20 vaporizing or flash distilling zone are subjected to fractionation and, as a special feature of the invention, reflux condensate resulting from said fractionation of the flash distilled vapors (hereinafter termed flash condensate, to distinguish it from reflux condensate from the various conversion stages of the process) is selectively returned to that conversion stage of the process employing the conditions most suitable for the further conversion of said flash condensate to 25 produce increased yields of the desired light product, usually motor fuel of high antiknock value.

Any desired number of successive conversion stages may be employed within the scope of the 30 present invention. The desired number may vary with different charging stocks as well as with the different results which it may be desirable to obtain and depend, in practice, upon an economic balance between the cost of operation and the 35 improved results which accrue from selective re-treatment of the intermediate products.

The attached diagrammatic drawing illustrates 40 one specific form of apparatus incorporating the features of the present invention in a three-stage process. A more detailed description of the op-

eration of the process is included in the following description of the drawing. Raw oil charging stock for the system is supplied from line 1 and valve 2 to pump 3 from which it may be fed through line 4, valve 5, preheating coils 6, 6' and 5 6'' located respectively within the fractionators 1, 1' and 1'', the preheated raw oil thence passing through line 8 and valves 9 and 10 to heating coil 11. It will be understood that the raw oil may be preheated in one, any combination or all 10 of the preheating coils 6, 6' and 6'' or may be preheated in any other well known manner, not shown in the drawing, or, when desired, may be supplied, all or in part, direct to heating coil 11 by well known means not shown in the drawing. 15

Heating coil 11 is located in a furnace 12 which supplies the heat required for the desired degree of conversion in this heating coil. The heated oil is discharged through line 13 and valve 14 into reaction chamber 15 wherein residual liquid is 20 separated from the vaporous conversion products. The residual liquid is withdrawn from chamber 15 through line 16 and valve 17 to further treatment, as will be later described. The vaporous conversion products pass from chamber 15 25 through outlet 18, in separating partition or deck 19 to fractionation in fractionator 1'. The vaporous conversion products remaining uncondensed in fractionator 1' are withdrawn through line 20 and valve 21 to condensation and cooling, 30 as will be later described.

Insufficiently converted heavy components of the vapors supplied to fractionator 1 are condensed in this zone as reflux condensate and are withdrawn from the lower portion of the fractionator through line 22 and valve 23 to pump 24 from which this reflux condensate from fractionator 1 is fed through line 25 and valve 26 to heating coil 11', for further conversion. 35

Furnace 12', of any suitable form, supplies the 40 heat recovered for the desired degree of conversion in heating coil 11' and the heated reflux condensate is discharged through line 13' and valve 14' into reaction chamber 15' wherein residual liquid separates from the vaporous conversion 45 products. The residual liquid is withdrawn from chamber 15' through line 16' and valve 17' to further treatment, as will be later described. The vaporous conversion products from chamber 15 50 pass through outlet 18', in separating partition 50 or deck 19', to fractionation in fractionator 1'. Vaporous products remaining uncondensed in fractionator 1' are withdrawn through line 20' and valve 21' to condensation, cooling and collection, as will be later described. 55

The insufficiently converted heavy components of the vapors supplied to fractionator 7' are condensed as reflux condensate in this zone and are withdrawn from the lower portion of the fractionator through line 22' and valve 23' to pump 24' from which this reflux condensate from fractionator 7' is fed through line 25' and valve 26' to further conversion in heating coil 11'.

The heat required for the desired degree of conversion in heating coil 11' is supplied from a furnace 12' of any suitable form and the heated reflux condensate is discharged from heating coil 11' through line 13' and valve 14' into reaction chamber 15' wherein residual liquid 15 separates from the vaporous conversion products. The residual liquid is withdrawn from chamber 15' through line 16' and valve 17' to further treatment, as will be later described. Vaporous conversion products pass from chamber 15' through outlet 18', in separating partition or deck 19', to fractionation in fractionator 1''. Vaporous conversion products remaining uncondensed in fractionator 1'' are withdrawn through line 20' and valve 21' to condensation, cooling and collection, as will be later described.

Insufficiently converted heavy components of the vapors condensed as reflux condensate in fractionator 1'' are withdrawn from the lower portion of this zone through line 22'' and pass, preferably, through valve 23'', in this line, to pump 24'' from which this reflux condensate is fed through line 25'' and valve 26'' into line 8, commingling therein with the raw oil charging stock for the system and passing therewith to heating coil 11, for further conversion.

Vaporous conversion products of the desired end-boiling point, withdrawn from fractionators 1, 1' and 1'', as already described, pass through line 27 and valve 28 to condensation and cooling 40 in condenser 29, from which the resulting distillate and uncondensable gas passes through line 30 and valve 31 to be collected in receiver 32. Uncondensable gas may be released from receiver 32 through line 33 and valve 34. Distillate 45 may be withdrawn from the receiver through line 35 and valve 36.

Residual liquids withdrawn from the chambers 15, 15' and 15'', as already described, commingle in line 37 and pass through valve 38, in 50 this line, to further vaporization in flash distilling chamber 39. Chamber 39 is preferably maintained at substantially reduced pressure relative to that employed in the reaction or separating zones 15, 15' and 15'', by means of which 55 reduction in pressure and the latent heat liberated thereby further vaporization of the residual oil is accomplished. The residual oil remaining unvaporized in chamber 39 may be withdrawn therefrom to storage or any desired further treatment through line 40 and valve 41. Vapors from chamber 39 pass through line 42 and valve 43 to fractionation in fractionator 44.

Vapors of the desired end-boiling point, corresponding to that of the vapors from fractionators 1, 1' and 1'', are withdrawn from the upper portion of fractionator 44 through line 45 and valve 46 and may pass to separate condensation, cooling and collection, by well known means not shown in the drawing, or preferably commingle 70 in line 27 with the vaporous products from the other fractionating zones of the system, passing therewith to condensation, cooling and collection in condenser 29 and receiver 32, as already described. When desired, a portion of the distillate from receiver 32 may be withdrawn through

line 47 and valve 48 to pump 49 from which it may be returned through line 50 to fractionator 44, or through similar lines not shown in the drawing, to any or all of the fractionating zones of the system to assist fractionation of the 5 vaporous conversion products therein.

Reflux condensate condensed in fractionator 44, boiling above the desired end-boiling point of the light vaporous product removed through line 45, as already described, is withdrawn from the 10 lower portion of this zone through line 52 and valve 53 to pump 54 from which it is fed through line 55, valve 56 and may pass through valve 57, in this line, into fractionator 1 or through line 55' and valve 57' into fractionator 1' or through 15 line 55'' and valve 57'' into fractionator 1''. The zone to which this product is returned will vary with different operating conditions, as well as with variations in the desired products produced by the process, this material being returned selectively to that stage of the system employing the 20 conditions best suited for its further conversion to produce maximum yields of the desired light products, usually comprising motor fuel of high antiknock value.

It is within the scope of the invention to supply a portion or all of the reflux condensate from the fractionator of the last conversion stage of the system (in this case fractionator 1'') to the fractionator (in this case 44) of the residuum flash 30 distilling stage of the system. Line 58 having valve 59 is provided in the apparatus illustrated for this purpose. In case this alternative is used, the reflux condensate from fractionator 1' or that portion of it supplied to fractionator 44, 35 commingles with the reflux condensate condensed in fractionator 44 and is returned to the same conversion stage wherein the reflux condensate from fractionator 44 is subjected to further conversion.

The various conversion stages of the process preferably employ substantial super-atmospheric pressures ranging, for example, from 100 to 800 pounds, or thereabouts per square inch. Substantially equalized or differential pressures may be employed between the various conversion stages. Preferably each successive conversion stage of the system employs conversion conditions more severe than those utilized in the preceding stage, conversion temperatures ranging, for example, from as low as 800° F. at the outlet from the heating coil of the first stage to as high as 1250° F., or thereabouts, at the outlet from the heating coil of the last stage. As already mentioned, the residuum flash distilling zone is 55 preferably operated at substantially reduced pressure relative to that employed in the reaction chambers and this reduced pressure may range, for example, from 100 pounds, or thereabouts, per square inch down to substantially 60 atmospheric pressure.

As a specific example of the operation of the process as it may be practiced in an apparatus such as illustrated and above described, the raw oil charging stock is a 30° A. P. I. gravity gas oil, 65 which is subjected in the heating coil of the primary stage of the system, to a temperature of about 930° F. at a super-atmospheric pressure of about 275 pounds per square inch. This pressure is substantially equalized in the succeeding reaction chamber and fractionator of this stage. Reflux condensate from the fractionator of the first stage is subjected in the heating coil of the second stage to a conversion temperature of approximately 950° F. at a super-atmospheric 70 75

pressure of about 400 pounds per square inch. This pressure is also substantially equalized in the reaction chamber and fractionator of this stage of the system. Reflux condensate from the 5 fractionator of the second stage is subjected in the heating coil of the third conversion stage to a temperature of about 1000° F. at a superatmospheric pressure of about 100 pounds per square inch. This pressure is also substantially 10 equalized in the succeeding reaction chamber and fractionator of this stage of the system. Reflux condensate from the third conversion stage is returned to the heating coil of the first stage. Residual oil from the three reaction chambers is 15 subjected to flash distillation at a reduced pressure of about 30 pounds per square inch. Flash condensate resulting from fractionation of the vapors from the flash distilling chamber is returned to the fractionator of the first conversion 20 stage whereby it is subjected to further treatment in the heating coil of the second stage. This operation may yield, per barrel of raw oil charging stock, about 68 percent of motor fuel, having an antiknock value equivalent to an 25 octane number of about 78, about 20 percent of good quality residual oil and about 1000 cubic feet of uncondensable gas.

In an operation such as above described, when the flash condensate is returned to the fractionator of the second conversion stage and thereby subjected, together with reflux condensate from this zone, the conversion conditions employed in the third conversion stage of the system, the antiknock value of the motor fuel product of the system is somewhat improved but the gas loss is increased and, for the same yield of motor fuel, a lower yield of residual oil is recovered.

Again in an operation similar to that first described, except that the flash condensate is returned to the fractionator of the third conversion stage and supplied therefrom, together with reflux condensate from this zone to the heating coil of the first conversion stage, the yield and 45 quality of residual oil may be increased at the expense of the antiknock value of the motor fuel product, the yield of motor fuel being approximately the same and the yield of gas somewhat lower.

50 I claim as my invention:

1. In a process for the conversion of hydrocarbon oil wherein the oil is subjected to conversion temperature at superatmospheric pressure in a heating coil and communicating enlarged reaction chamber, wherein vaporous and residual liquid conversion products separate, vapors from the reaction chamber subjected to fractionation, reflux condensate from the fractionator subjected to further conversion at superatmospheric pressure in a separate heating coil and communicating enlarged reaction chamber wherein vaporous and residual liquid conversion products separate, vapors from said separate reaction chamber subjected to separate fractionation, reflux condensate from said separate fractionator subjected to further conversion at superatmospheric pressure in another separate heating coil and communicating enlarged reaction chamber wherein vaporous and residual liquid conversion products separate and vapors from the last mentioned reaction chamber subjected to separate fractionation, and the overhead vapors from the fractionation stages condensed and collected, the improvement which comprises 70 withdrawing unvaporized residual oil from each 75

reaction chamber, commingling the residual oils and subjecting them to further vaporization at reduced pressure, subjecting the resulting vapors to fractionation, supplying to the last mentioned fractionating stage reflux condensate from the 5 fractionator to which vapors from the last mentioned reaction chamber are supplied and returning reflux condensate from said last mentioned fractionating stage to the system for further conversion.

10 2. A process of the character defined in claim 1, wherein reflux condensate from said last mentioned fractionating stage is returned to at least one heating coil of the system.

15 3. A process of the character defined in claim 1, wherein portions of the reflux condensate from said last mentioned fractionating stage are returned to more than one heating coil of the system.

20 4. A cracking process which comprises heating hydrocarbon oil to cracking temperature under pressure and separating the same into vapors and unvaporized oil, introducing the vapors to a fractionating zone and fractionating the same therein to condense and separate insufficiently 25 cracked fractions thereof, flash distilling the unvaporized oil by pressure reduction and dephlegmating the flashed vapors independently of the first named vapors, introducing resultant flash reflux to said fractionating zone as a dephlegmating medium for the vapors therein thereby forming a composite reflux condensate of the insufficiently cracked fractions and flashed fractions, subjecting such composite reflux condensate to independently controlled cracking conditions 30 of temperature and pressure, fractionating the additional cracked vapors thus formed independently of the flashed vapors and flash distilling the unvaporized portion of the independently cracked composite reflux condensate in admixture with 35 said unvaporized oil, and finally condensing the fractionated vapors.

40 5. A conversion process which comprises subjecting hydrocarbon oil to cracking temperature under superatmospheric pressure in a heating coil 45 and communicating enlarged reaction chamber, separating vapors from residual oil in the chamber, fractionating the vapors and subjecting resultant reflux condensate to further conversion at superatmospheric pressure in a separate heating coil and communicating enlarged reaction chamber, separating vapors from residual oil in the last-named chamber and fractionating these vapors independently of the first-named vapors, withdrawing residual oil from each of the 55 chambers, commingling the residual oils and subjecting them to further vaporization at reduced pressure, fractionating the resultant vapors in contact with reflux condensate formed in the second-mentioned fractionating step, returning 60 reflux condensate from the third-mentioned fractionation to the system for further conversion, and finally condensing and collecting the overhead vapors from the fractionating stages.

65 6. A conversion process which comprises subjecting hydrocarbon oil to cracking temperature under superatmospheric pressure in a heated coil and communicating enlarged reaction chamber, separating vapors from residual oil in the chamber, fractionating the vapors and subjecting 70 resultant reflux condensate to further conversion at superatmospheric pressure in a separate heating coil and communicating enlarged reaction chamber, separating vapors from residual oil in the last-named chamber and fractionating these vapors 75

independently of the first-named vapors, withdrawing residual oil from each of the chambers, commingling the residual oils and subjecting them to further vaporization at reduced pressure, fractionating the resultant vapors in contact with reflux condensate formed in the second-mentioned fractionating step, returning reflux condensate from the third-mentioned fractionation to the first-named heating coil for further conversion, and finally condensing and collecting the overhead vapors from the fractionating stages.

7. A conversion process which comprises subjecting hydrocarbon oil to cracking temperature under superatmospheric pressure in a heating coil and communicating enlarged reaction chamber, separating vapors from residual oil in the chamber, fractionating the vapors and subjecting resultant reflux condensate to further conversion at superatmospheric pressure in a separate heating coil and communicating enlarged reaction chamber, separating vapors from residual oil in the last-named chamber and fractionating these vapors independently of the first-named vapors, withdrawing residual oil from each of the chambers, commingling the residual oils and subjecting them to further vaporization at reduced pressure, fractionating the resultant vapors in contact with reflux condensate formed in the second-mentioned fractionating step, returning reflux condensate from the third-mentioned fractionation to the second-named heating coil for further conversion, and finally condensing and collecting the overhead vapors from the fractionating stages.

8. A conversion process which comprises simultaneously subjecting hydrocarbon oils to independently controlled cracking conditions of temperature and pressure in a series of cracking zones maintained at successively higher temperatures, separately removing vapors and unvaporized oil from each of said zones and introducing the vapors from each of the cracking zones to a separate fractionating zone, fractionating the vapors in the fractionating zones to condense heavier fractions thereof, supplying reflux condensate from a fractionating zone receiving vapors from a relatively low temperature cracking zone to the cracking zone of next higher temperature in the series, combining the unvaporized oils withdrawn from the cracking zones and flash distilling the resultant mixture by pressure reduction, fractionating the resultant flashed vapors independently of the vapors from the cracking zones, introducing flash reflux thus formed into said fractionating zone receiving vapors from a relatively low temperature cracking zone as a dephlegmating medium and to be supplied with said reflux condensate to said cracking zone of

next higher temperature, and finally condensing the fractionated vapors.

9. A hydrocarbon oil conversion process which comprises subjecting the charging oil to cracking conditions of temperature and pressure in a first cracking zone, separately removing vapors and unvaporized oil from said zone, fractionating the vapors and supplying resultant reflux condensate to a second cracking zone, cracking the reflux condensate in said second zone at higher temperature than the charging oil in said first zone and separately removing vapors and unvaporized oil from the second zone, fractionating the vapors from the second zone and combining the unvaporized oil from this zone with that withdrawn from the first zone, flash distilling the resultant mixture of unvaporized oils by pressure reduction, fractionating the resultant flashed vapors and introducing flash reflux thus formed into contact with the first-named vapors undergoing fractionation as a dephlegmating medium thereof and to be supplied with said reflux condensate to the second cracking zone, and finally condensing the fractionated vapors.

10. A conversion process which comprises simultaneously subjecting hydrocarbon oils to independently controlled cracking conditions of temperature and pressure in a series of at least three cracking zones maintained at successively higher temperatures, separately removing vapors and unvaporized oil from each of said zones and introducing the vapors from each of the cracking zones to a separate fractionating zone, fractionating the vapors in the fractionating zones to condense heavier fractions thereof, supplying to the first or lowest temperature cracking zone in the series reflux condensate formed in the fractionating zone receiving vapors from the last or highest temperature cracking zone of the series, supplying to the second cracking zone in the series reflux condensate formed in the fractionating zone receiving vapors from said first cracking zone, supplying to the third cracking zone in the series reflux condensate formed in the fractionating zone receiving vapors from said second cracking zone, combining the unvaporized oils withdrawn from the cracking zones and flash distilling the resultant mixture by pressure reduction, fractionating the resultant flashed vapors independently of the vapors from the cracking zones, introducing flash reflux thus formed into said fractionating zone receiving vapors from the last cracking zone of the series as a dephlegmating medium and to be supplied with the first-named reflux condensate to said first cracking zone, and finally condensing the fractionated vapors.

JEAN DELATTRE SEGUY.
